CLAIM

The ornamental design for a watch with neon-like illumination ring groove on crystal underside, as shown and described.

DESCRIPTION

FIG. 1 is a front elevational view of a watch with neon-like illumination ring groove on crystal underside showing our new design, the broken-line showings of band-ends are environmental only and form no part of the claimed design;

FIG. 2 is a right side elevational view thereof;

FIG. 3 is a left side elevational view thereof;

FIG. 4 is a bottom plan view thereof;

FIG. 5 is a top plan view thereof;

FIG. 6 is a rear elevational view thereof
